GUY C. WILKINSON AND MEAD HEDGLON, OF SYRACUSE, NEW YORK, ASSIGNEES
TO SYRACUSE WASHING MACHINE CORPORATION, OF SYRACUSE, NEW YORK, A
CORPORATION OF NEW YORK.

PLUNGER-OPERATING MECHANISM.

Application filed October 25, 1921. Serial No. 510,331.

To all whom it may concern:

Be it known that we, GUY C. WILKINSON and MEAD HEDGLON, citizens of the United States, and residents of Syracuse, in the county of Onondaga, in the State of New York, have invented new and useful Improvements in Plunger-Operating Mechanism, of which the following, taken in connection with the accompanying drawings, is a full, clear, and exact description.

This invention relates to a plunger operating mechanism for washing machines, of the general type disclosed in patent to Zuill No. 1,021,498 embodying a vertically reciprocating plunger that imparts desired movements to the vacuum cup devices of the machine.

The main object of this invention is to provide mechanism for delivering power to the piston in a straight line conforming to the axis of the piston. This feature has many advantages in that it eliminates side thrusts from the bearings in which the piston is operating, and even permits the use 25 of the single bearing for the piston, should that be desirable.

Other objects relate more specifically to the arrangement and construction of the mechanism for effecting straight-line movement of the piston such as simplification of the mechanism by the elimination of usually required parts, such as for instance, equalizing devices, etc.

Further, our invention provides an apparatus of simple construction and operation that is more easily assembled than those heretofore used and that eliminates practically all danger of the mechanism becoming out of alignment after being properly 40 assembled.

Other objects and advantages relate to the details of construction and form of the mechanism, all as will more fully appear from the following description, taken in connection with the accompanying drawings, in which:—

Figure 1 is an elevation of the mechanism of our invention.

Figures 2 and 3 are diagrammatic illustrations of the mechanism in different operative positions.

For the purpose of illustrating our invention, we have indicated a frame —1— which may be of any form and construction, pref-

erably from some portion of which mechanism hereinafter described is supported. The machine to which our invention is applied is of that type which embodies a piston vertically reciprocating through the bottom of the tub for actuating the usual vacuum cup devices of this type of machine.

The mechanism we have designed for this purpose consists of a swinging link or compensating leg —2— that may be pivoted at its upper end upon pin —3— carried by or formed in connection with the frame —1— of the machine. The main lever or walking beam —4— of the piston-operating mechanism is hinged or pivoted at one end upon the pin —5— formed at the lower end of the swinging leg —2—, and the opposite

end of the lever —4— is formed with a yoke, the opposite walls —6— of which are formed with openings or journals for receiving respective trunnions —7— extending at opposite sides of a trunnion block —8— mounted on the lower end of the piston —9— of the washing machine. Any suitable mechanism may be provided for securing the walls —6— in proper position with respect to the trunnions —7—. The main lever —4— is actuated for the purpose of reciprocating piston —9— by means of a pitman —10— mounted at its lower end upon a pin —11— formed in connection with the main lever —4— and at its upper end upon a pin —12— formed in connection with a crank-arm —13— rigidly mounted upon the main shaft —14— of the washing machine.

It will be obvious that as the main shaft —14— rotates the pin —12— will travel as indicated in dotted line, Figure 1, carrying with it the upper end of the pitman —10—, thereby moving the main lever —4— about its pivot —5— to raise and lower the plunger —9—. For the purpose of causing the main lever —4— to deliver power to the piston or plunger —9— in a straight-line conforming substantially to the axis of the plunger, a radius bar —15— is provided having one end pivotally mounted upon a pin —16— which may be rigidly carried

from any part of the machine so that it remains in stationary position during the operation of the mechanism. The opposite end of the radius bar —15— is pivotally connected to the main lever —4— in any suitable manner and as shown, one of the

members, as for instance the radius bar —15— is provided with a pin —17— extending through the other member to provide such a pivotal connection.

5 It will be obvious from the disclosure that as the main shaft —14— rotates, carrying with it the crank-arm —13— and pitman —10— that the main lever —4— will be raised and lowered to raise and lower the piston or plunger —9—, and that as the main lever —4— is raised and lowered, it will be caused to reciprocate by means of radius bar —15— to an extent sufficient to cause the application of power to the 10 plunger —9— to be in a straight line conforming to the axis of the plunger. This movement of the main lever —4— is permitted by reason of the fact that its pivot —5— is upon a leg —2— that is free to 15 swing about the pin —3— carried in a stationary manner by the main frame.

The lower end of the link —2— carrying the pivotal pin —5— for the lever —4— is adapted to swing toward and from the 20 plunger —9— in substantially the same horizontal plane as that of the pivotal stud —16— for the radius bar —15— while the throw of the crank arm —13— which is connected to the lever —4— by means 25 of the pitman —10— is made to rock the lever —4— upon its fulcrum —5— equal distances above and below the horizontal plane of the axis of the pivotal stud —16— of the radius bar —15—.

30 This radius bar —15— extends from its pivotal stud —16— toward the fulcrum —5— of the lever —4— and is pivoted to said lever at —17— between the pivots —5— and —11— and therefore, its pivotal pin 35 —17— will travel through a vertical arc equal distances above and below the horizontal plane of the axis of the pivotal stud —16— as the lever and plunger —9— carried thereby are moved vertically by the 40 crank arm —13— and pitman —10—.

The length of the radius bar —15— depends upon the throw of the crank arm —13— and therefore, upon the movement of 45 the lever —4— from one extreme position to another but is made to conform to the changing position of the pivot —5— with the link —2— under the condition that the plunger —9— is moved rectilinearly of its axis. For example, assuming that the 50 plunger —9— is moved rectilinearly of its axis from the position shown in Figure 1, it is evident that as the adjacent end of the lever —4— approaches the horizontal plane its opposite end connected to the lower 55 end of the link —2— will be moved a short distance to the right, and as the lever continues to move to its extreme upward limit, the pivot —5— will be returned to its starting position through the same distance and 60 it is this amount of movement of the pivot

—5— which determines radial length of the bar —15— which is proportionate to the length and angular movement of the lever —4—.

That is, the arc of movement of the pivotal pin —17— of the radius bar —15— which fulcrumed at —16— in the horizontal plane of the pivot —5— is of such radius as to cause the pivotal pin —7— to travel rectilinearly of the axis of the plunger —9— it being understood that the middle ordinates of the arcs of movement of the pivotal pins —17— and —7— are also proportionate in that the middle ordinate of the arc of movement of the pin —17— corresponds to the endwise movement of the lever —4— required to produce the desired rectilinear movement of the pin —7—.

As a feature of construction, it will be noted that the pin —11— is disposed between the pivot —17— and the trunnions —7— and that the main lever —4— at the pivot —11— is bent downwardly so that such pivot lies considerably below the pivot —17— and the pivot of the walls —6— of the yoke end of the lever, permitting efficient operation with considerable economy of space and material.

Although we have shown and described a specific construction of mechanism and a particular form and arrangement of the parts thereof, as illustrative of a perhaps preferred embodiment of our invention, we do not desire to limit ourselves to the details of form, construction or arrangement of the mechanism, as various changes may be made without departing from the invention as set forth in the appended claims.

We claim:

1. A plunger operating mechanism comprising in combination with a vertically movable plunger, a walking beam fulcrumed at one end to permit longitudinal movement of the beam and having its other end operatively connected to the plunger, a rotary driving element movable about a fixed axis above the intermediate portion of the walking beam, a pitman having one end eccentrically pivoted to the driving element and its other end pivotally connected to the intermediate portion of the walking beam for rocking said beam upon its fulcrum and thereby reciprocating the plunger, and a radius rod having one end pivoted to swing about a fixed axis in the vertical plane of and below the axis of the driving element and its other end pivotally connected to the walking beam between the fulcrum of said beam and the pivotal connection of the pitman with the beam.

2. A plunger operating mechanism comprising in combination with a vertically movable plunger, an upright link having its upper end pivoted to swing about a fixed axis, a walking beam having one end ful-

crummed on the lower end of the link and its fulcrum, and a radius bar having one end pivoted to swing about a fixed axis in the vertical plane of and below the axis of the driving element and its other end pivoted to the walking beam between the pitman and link.

5 between the link and plunger and above the intermediate portion of the walking beam, a pitman having one end eccentrically pivoted to the driving element and its other end pivoted to the intermediate portion of the

10 walking beam for rocking said beam upon

In witness whereof we have hereunto set our hands this 19th day of October, 1921.

GUY C. WILKINSON.
